UNITED STATES PATENT OFFICE.

HENRY L. PALMER, OF BROOKLYN, NEW YORK.

DESIGN FOR AN EASEL FRAME OR HOLDER.

SPECIFICATION forming part of Design No. 16,199, dated August 11, 1885.

Application filed February 12, 1885. Term of patent 14 years.

To all whom it may concern:

Be it known that I, HENRY L. PALMER, a citizen of the United States, residing at No. 160 Clinton street, in the city of Brooklyn, county of Kings, and State of New York, have invented a new and original Design for an Easel Frame or Holder and various other objects, of which the following is a specification, reference being had to the accompanying drawings, forming part thereof.

Figure 1 is a front elevation of my new design for an easel frame or holder. Fig. 2 is a side elevation, and Fig. 3 is a sectional view on the line $x x$, Fig. 1.

The leading feature of my design consists in a four-sided outline easel in the form of a scroll, the upper and lower sides parallel and horizontal, and the two remaining sides of which are also parallel and deflected at a slight angle to a perpendicular, provided also with a rolling top and bottom edge, as in the recognized form of a scroll, and having an open face "sight" or designated location for the plaque, photograph, picture, or other object, as stated, occupying a central position in full view, as in any ordinary frame, but surrounded by a beveled bead, border, rim, or downwardly projecting flange, B, within which is a central opening, S'.

S is the scroll, and S' the sight or opening 30 surrounded by the irregular spaces S², which are finished at top and bottom by the rolling top and bottom edges, S³. B is a beveled bead, border, rim, or internal flange surrounding the sight or center. Nor need the scroll stand 35 at the precise angle or angles shown, as that may be varied at will to suit the taste; and the angle may be, as shown, to the right of the perpendicular; or it may be reversed, the scroll being deflected to the left. 40

I claim—

The design for an easel frame or holder for pictures or other objects, consisting of a four-sided figure curved at the top and bottom like a scroll, the sides of the holder being inclined 45 so as to form two acute and two obtuse angles with the top and bottom, the same having a surface of repeated spots, S², and provided with a central opening, S', surrounded with a curved inner wall or flange, B, as herein 50 shown and set forth.

HENRY L. PALMER.
